UNITED STATES PATENT OFFICE.

JAMES H. RAND, OF NORTH TONAWANDA, NEW YORK.

INDEX.

1,317,642.

Specification of Letters Patent. Patented Sept. 30, 1919.

Application filed November 11, 1918. Serial No. 262,073.

To all whom it may concern:

Be it known that I, JAMES H. RAND, citizen of United States, and resident of North Tonawanda, in the county of Niagara 5 and State of New York, have invented new and useful Improvements in Indexes, of which the following is a specification.

This invention relates to card indexes, and has to do particularly with the novel 10 construction of index cards for use in card indexes of the overlapping-card, visible index type.

In the accompanying drawings which illustrate certain preferred embodiments of 15 the invention,

Figure 1 is a front elevation of a part of a card index wherein the cards are mounted in a frame in depending and overlapped position;

20 Fig. 2 is a section on line 2—2 of Fig. 1; Fig. 3 is a front view, partly broken away, of one of the cards shown in Fig. 1;

Fig. 4 is an enlarged section on line 4—4 of Fig. 1;

25 Fig. 5 is a rear view of said card, partly broken away;

Fig. 6 is a plan, partly broken away, of the blank from which said card is formed;

30 Fig. 7 is a front elevation of a part of a card index wherein the cards are mounted in a frame in upstanding and overlapped position;

Fig. 8 is a section on line 8—8 of Fig. 7; Fig. 9 is a rear view, partly broken away, 35 of one of the cards shown in Fig. 7;

Fig. 10 is an enlarged section on line 10—10 of Fig. 9; and

40 Fig. 11 is a plan, partly broken away, of the blank from which the cards shown in Figs. 7 to 10 are made.

Referring first to the form shown in Figs. 1 to 6, the index card 1, of card-board or other suitable sheet material has extending along one margin, and preferably formed 45 integrally with the body of the card, a stiffening strip composed of a plurality of narrow folded sections superposed one upon another. Said stiffening strip may be formed by folding the card over upon itself on line 50 2 (Fig. 6), then folding it reversely on line 3, and then reversely on line 4, thus making a number of narrow, reversely folded, su-

perposed sections. The ultimate section 5 is made wider than the intermediate folded sections 6 and 7, to provide a tongue which 55 engages the margin of an adjacent index card when a series of such cards are nested as shown in Fig. 2, and arranged in a frame in overlapped relation.

The sections, thus folded over one upon another, are fastened together by a row of staples 8, which pass through the several piles or folds, or by cement or other suitable means. When staples 8 are used the staples at the ends preferably pass around 65 the extremities of the stiffening strip to bind the several plies or folds together at their ends. The folded stiffening strip thus formed projects at each end beyond the body 70 of the card, and the cards may be mounted in an index frame F of usual construction by inserting the ends of the strip under the flanges f.

The multiple strip thus formed of a number of superposed, narrow, folded sections, 75 suitably fastened together into a unitary structure, performs the functions of the usual relatively heavy bar or strip of bristol board attached to the edge of the card. It possesses sufficient stiffness to hold the card 80 securely and flat in the frame, and at the same time sufficient resiliency to allow it to be sprung or buckled to insert the ends in the frame. It constitutes not only means to hold the cards in the frame but also 85 means to space the cards relatively to one another so that their free margins will be exposed to display indexing characters. And the several plies or folds possess sufficient thickness to separate the tongue 5 90 from the body of the card and leave a space to receive the margin of the next adjacent card with comparatively little distortion or deflection of the tongue or the body of the card.

95 The invention is equally adaptable to overlapping cards of the upstanding type, as shown in Figs. 7 to 11. In this modification the cards 1^a have the stiffening strip formed at the bottom. Its ends are held 100 in the frame F by the flanges f, while the body of the card extends upward, and may be provided at its free edge with projections 9 which rest on the front face of the

flanges *f*. Similar lateral projections 10 at the bottom of the card extending under the flanges *f*, have sufficient vertical dimensions to hold the card upright in the frame. In 5 other respects this modification is like the one first described, and corresponding reference characters indicate corresponding parts.

Where the invention is used in depending cards as shown in Figs. 1 to 6 the card is 10 preferably creased along line 11, beside and parallel to the row of staples 8, to form a hinge between the body of the card and the folded stiffening strip, thus permitting the card to be easily swung forward and 15 upward away from the frame. Where it is used in upstanding cards as shown in Figs. 7 to 11 no such hinge is used as the card must be held upright by its own stiffness and is merely bent or deflected away from 20 the frame if a concealed card is to be inspected; but the tongue 5 of this form is preferably bent a little to the rear on line 12 so as to stand open sufficiently to easily receive the edge of the next card above when 25 the cards are being assembled.

The terms card and index card, as used throughout the specification and claims, denote any index element of the character described, whether made of card-board, paper, or other suitable sheet material, and whether used as the sheets on which the 30 entries are directly made, or merely as holders to which are attached other cards or sheets on which the entries are made.

35 A notch or cut 5^a extending inwardly from the free edge of the tongue 5 is formed in the tongue to prevent the tongue from buckling when the card is bent or sprung transversely of the tongue to insert the ends 40 of the stiffening strip under the flanges of the frame.

I claim:

45 1. An index card having a stiffening strip formed of a plurality of narrow folded sections superposed one upon another, and staples passing through the several superposed folded sections to fasten the same together.

50 2. An index card having a stiffening strip extending along one margin and formed of a plurality of narrow folded sections superposed one upon another, and means to fasten the superposed folded sections together.

55 3. An index card having a stiffening strip formed of a plurality of narrow folded sections superposed one upon another, and means to fasten the superposed folded sections together, said folded stiffening strip projecting at each end beyond the body of the card.

60 4. An index card having a stiffening strip extending along one margin formed of a plurality of narrow folded sections superposed one upon another, the ultimate folded section being wider than the intermediate sec-

tions and forming a tongue adapted to engage the margin of an adjacent index card 65 when a series of such cards are arranged in overlapped relation, and means to fasten the superposed folded sections together.

5. An index card having a stiffening strip 70 extending along one margin formed of a plurality of narrow reversely folded sections superposed one upon another, the ultimate folded section being wider than the intermediate sections and forming a tongue 75 adapted to engage the margin of an adjacent index card when a series of such cards are arranged in overlapped relation, and means to fasten the superposed folded sections together.

6. An index card having a stiffening strip formed of a plurality of narrow folded sections superposed one upon another, and means to fasten the superposed folded sections together, said folded stiffening strip 85 projecting at each end beyond the body of the card, and the body of the card being hinged to the stiffening strip.

7. An index card of sheet material having 90 an integrally formed stiffening strip extending along one margin composed of a plurality of narrow reversely folded sections superposed one upon another, the ultimate folded section being wider than the intermediate sections and forming a tongue 95 adapted to engage the margin of an adjacent index card when a series of such cards are arranged in overlapped relation, and a row of staples passing through the several superposed folded sections to fasten 100 the same together.

8. An index card of sheet material having 105 an integrally formed stiffening strip extending along one margin composed of a plurality of narrow reversely folded sections superposed one upon another, the ultimate folded section being wider than the intermediate sections and forming a tongue adapted to engage the margin of an adjacent index card when a series of such cards are arranged in overlapped relation, and a row of staples passing through the several superposed folded sections to fasten the same together, said card being creased along 110 a line beside and parallel to the row of staples to form a hinge between the body of the card and said folded stiffening strip.

9. An index card of sheet material having 115 a tongue extending along one margin, said tongue being provided with a cut extending inwardly from the free edge of the tongue to prevent the buckling of the tongue when the card is bent transversely of the tongue.

10. An index card having a stiffening strip 120 extending along one margin formed of a plurality of narrow folded sections superposed one upon another, the ultimate folded

section being wider than the intermediate sections and forming a tongue adapted to engage the margin of an adjacent index card when a series of such cards are ar-

5 ranged in overlapped relation, and means to fasten the superposed folded sections together, said tongue being provided with a

cut extending inwardly from the free edge of the tongue to prevent the tongue from buckling when the card is bent transversely 10 of the tongue.

Signed by me at North Tonawanda, N. Y., this 6th day of November, 1918.

JAMES H. RAND.
